MOUNT FOR MACHINE GUNS.

Application filed October 9, 1925. Serial No. 61,615.

(GRANTED UNDER THE ACT OF MARCH 3, 1883; 22 STAT. L. 625.)

This invention relates to a mount for machine guns.

A machine gun in order to accomplish the purpose for which it is designed must be provided with a mount which, while insuring rigidity, stability, and ease of manipulation of the gun, is limited in weight so as to retain its mobility.

In devising a mount possessing in the highest possible degree the foregoing essential requirements and characteristics it is necessary that the resultant thrust applied to the mount be within its base or at least coincident with its trail leg in order to reduce the oscillation of the mount about the trail foot and also to eliminate the tendency of the cradle to slip with respect to the mount. This involves a consideration of the position of the trunnions of the gun or the cradle with respect to the component forces acting upon the gun. While the theoretically correct position of the trunnions may be determined at a certain point their actual location must be established with a view to permitting unrestricted feed and ejection of the cartridges, movement of the gun in azimuth and elevation, adjustment of the mount to the firing and traveling position, and it is also desirable that the mount be capable of supporting an antiaircraft adaptor for high angle firing.

The operation of an automatic gun presents additional complications in that the reciprocation of the recoiling parts is causing a continuous shifting of the center of gravity of the gun and coupled to this is the fact that because of the rapidity of firing the reactions of successive shots are transmitted to the mount in different phases of its vibration.

The actual location of the trunnions involves besides a consideration of all of the foregoing factors the position which is best adapted for varying elevations of the gun.

Accordingly in the present invention the gun is rigidly attached to a cradle the axis of the trunnions of which has a point which is coincident with a point in the vertical axis of the mount which is also the axis of traverse. The cradle is so constructed that with the gun in position therein the center of gravity of the recoiling parts of the gun when in battery will lie in a plane of the

axis of the trunnions substantially in the point when the axis of traverse pierces such plane, which plane, is approximately midway between the center line of bore along which the powder gases react and the center line of acceleration along which this force is exerted. The trunnions are further positioned in rear of the center of gravity of the gun both when in battery and when at the end of recoil, the latter center of gravity being coincident with the forward attachment of the gun to the cradle. By virtue of the foregoing dispositions and the particularly low mounting which may be obtained thereby the resultant thrust is applied to the mount substantially along the line of the trail leg.

While conforming to the requirements necessary in properly locating the trunnions the cradle is so designed as not to obstruct the vertical pintle of the cradle support which is recessed to receive a standard for mounting the gun for antiaircraft firing without removal of the cradle. Means are also provided for supporting the gun in the exact position to receive the attaching pins.

To these and other ends, our invention consists in the construction, arrangement and combination of elements, described hereinafter and pointed out in the claims forming a part of this specification.

A practical embodiment of the invention is illustrated in the accompanying drawings, wherein:

Fig. 1 is a view in side elevation of a mount constructed in accordance with the invention;

Fig. 2 is a plan view thereof with the gun removed;

Fig. 3 is a sectional view on the line 3-3 of Fig. 1; and

Fig. 4 is a reduced view in elevation showing the antiaircraft adaptor in place.

Referring to the drawings by numerals and characters of reference:

The mount A, which preferably assumes the form of a tripod support, consists of a head or socket member 5 equipped with the usual front legs 6 and trail leg 7.

Mounted by the socket member for movement in azimuth is a unitary cradle support B comprising a yoke 8, a centrally apertured annular base 9 resting on the top of the

socket member 5, and a hollow pindle 10. The yoke arms carry at their upper ends trunnion pins 11—11 the axis of which lies in a plane of the vertical axis of the support, 5 and which mount a cradle C. The cradle consists of a pair of plates 12 connected by rods 13—13 encircled by spacing sleeves 13', and which are so located as to support the gun D in the exact position of its attachment. This position is determined when the receiver of the gun bears against the forward spacer which supports the water jacket as clearly shown in Figure 1. This provision will considerably reduce the time required to 10 mount the gun in coming into action and will be of special significance when, by reason of lack of cover, the gun crew is obliged to operate from a prone position.

The gun is rigidly secured to the cradle in 20 any suitable manner, a convenient attachment being shown which consists in inserting bolts 14 through apertures 15—15 in the cradle plates and apertured lugs 16—16 on the gun. The front attachment is forwardly 25 of the cradle trunnions and is located in a plane perpendicular to the axis of the gun which plane contains the center of gravity of the gun when the recoiling parts are at the end of the recoil stroke. The center of gravity of the gun when the recoiling parts are 30 in battery is naturally still further forward and is indicated at the point E substantially in prolongation of the trail. Inasmuch as the center of gravity is at all times forwardly of the trunnions so as to compensate 35 for the natural inclination of the gunner to bear down on the rear end of the gun, stability during firing is assured and the direction of the resultant force of the thrust on 40 the mount will be substantially on the line of the trail leg.

Considering now the vertical position of the trunnions with respect to the gun it may be stated that theoretically the center line of 45 acceleration of the gun should coincide with the center line of bore. This condition is impractical in machine guns, the former being above the latter. The correct position 50 of the trunnions under these circumstances has been determined to be a point midway between the two and they are so located in the present invention. In this position the trunnion axis has a point coincident or substantially coincident with the center of gravity 55 of the recoiling parts of the gun when in battery.

With regard to the vertical position of the trunnions with respect to the base 9 of the yoke it is to be noted that in the interest of 60 stability this distance, which is the height of the yoke arms, should be as small as is consistent with the maximum inclination to be given the gun. In the present mount the typical rear elevating mechanism which is 65 generally employed is dispensed with there-

by permitting greater range of movement of the cradle and in the position of maximum elevation it will lie approximately parallel to and adjacent the trail leg. This result is directly the effect of the favorable low mounting of the gun with respect to the base of the yoke. The rear elevating mechanism is unnecessary from the standpoint of providing a support for the rear end of the gun because of the well-balanced features of the 70 assembly.

Any suitable locking device may be provided for holding the cradle in the adjusted position of elevation, a preferred form consisting of a headed bolt 17 mounted on the 75 base 9 of the support and threadedly carrying a jamming handle 18. The cradle plates are formed with arcuate portions 12' adapted to be clamped between the locking unit. In the drawings only one of the cradle plates 80 is shown clamped, but if desired, a locking unit may readily be made to engage both the plates.

In firing against rapidly moving aerial targets the gun must be capable of unrestrained movement in azimuth and elevation and to this end a high mounting is desirable. Accordingly, there is provided a standard 19 having a swiveled yoke 20 for trunnioning the gun and which may be mounted vertically 25 in the support B without removal of the cradle. The bolt 21 in the tripod head unit may extend upwards into the pindle so that the standard may be threaded thereon. When not in use the standard may conveniently 30 be strapped to the trail leg.

Encircling the base 9 of the cradle support and resting on the socket member 5 is an azimuth scale ring 22 whose reading face 22' is cut at an angle of 45° so that the 105 reader need not be obliged to raise his head to observe the scale reading.

While in the foregoing there has been illustrated and described such combination and arrangement of elements as constitute 110 the preferred embodiment of the invention, it is nevertheless desired to emphasize the fact that interpretation of the invention should only be conclusive when made in the light of the subjoined claims.

We claim:

1. A mount for machine guns embodying a socket member provided with legs, a yoke rotatably mounted in said member, a cradle having spaced plates trunnioned in the yoke 115 and adapted to carry a gun between the plates, the axis of the trunnions having a point coincident with a point in the vertical axis of the socket member and the center of gravity of the recoiling parts of the 120 gun when in battery such point being in a line midway between and parallel to the center line of bore and center line of acceleration of the gun, said trunnions further 125 positioned to such an amount in rear of the 130

- center of gravity of the gun that, in battery, the center of gravity may be substantially in line with the trail leg and at the end of recoil the center of gravity will 5 lie in a plane perpendicular to the center line of the gun and passing through the forward attachment of the gun to the cradle, said trunnions being also positioned but a short distance above the base of the yoke so 10 that when the gun is in the position of normal elevation it will lie close to the trail leg.
2. A mount for machine guns embodying a socket member provided with legs, a yoke rotatably mounted in said member, a cradle 15 having spaced plates trunnioned in the yoke and adapted to carry a gun between the plates, the axis of the trunnions having a point coincident with the center of gravity of the recoiling parts of the gun when in battery such point being in a line midway between and parallel to the center line of bore and center line of acceleration of the gun, said trunnions further positioned to 20 such an amount in rear of the center of gravity of the gun that, in battery, the center of gravity may be substantially in prolongation of the trail leg, said trunnions being also positioned but a short distance above the base of the yoke so that when the 25 gun is in the position of normal elevation it will lie close to the trail leg.
3. A mount for machine guns embodying a socket member provided with legs, a yoke rotatably mounted in said member, a cradle 30 having spaced plates trunnioned in the yoke and adapted to carry a gun between the plates, the axis of the trunnions having a point coincident with the center of gravity of the recoiling parts of the gun when in battery, such point being in a line midway between and parallel to the center line of bore and center line of acceleration of the gun, said trunnions further positioned in rear of the center of gravity of the gun both 35 in battery and at the end of recoil, and said trunnions being also positioned but a short distance above the base of the yoke so that when the gun is in the position of normal elevation it will lie close to the trail leg.
4. A mount for machine guns embodying a socket member provided with legs, a yoke rotatably mounted in said member, a cradle 40 having spaced plates trunnioned in the yoke and adapted to carry a gun between the plates, the axis of the trunnions having a point coincident with the center of gravity of the recoiling parts of the gun when in battery and at the end of recoil the center of gravity will lie in a plane perpendicular to the center line of the gun and passing through the forward attachment of the gun to the cradle.
5. A mount for machine guns embodying a tripod, a yoke rotatably mounted in the 45 tripod head, a cradle trunnioned in the yoke and adapted to secure a gun, the axis of the trunnions having a point coincident with the center of gravity of the recoiling parts of the gun when in battery, such point being in a line midway between and parallel to the center line of bore and center line of acceleration of the gun, and said trunnions further positioned in rear of the centers of gravity of the gun both 50 in battery and at the end of recoil.
6. A mount for machine guns embodying a support, a yoke rotatably mounted thereon, a cradle trunnioned in the yoke and adapted to secure a gun, the axis of the 55 trunnions having a point coincident with a point in the vertical axis of the support and the center of gravity of the recoiling parts of the gun when in battery and such point being in a line midway between and parallel to the center line of bore and the center line of acceleration of the gun.
7. A mount for machine guns, embodying a support, a yoke rotatably mounted thereon, a cradle trunnioned in the yoke and 60 adapted to secure a gun, the axis of the trunnions having a point coincident with the center of gravity of the recoiling parts of the gun when in battery and being in a line midway between and parallel to the center line of bore and the center line of acceleration of the gun.
8. A mount for machine guns embodying a support, a yoke rotatably mounted thereon, a cradle trunnioned in the yoke and 65 adapted to secure a gun, the trunnions being located midway between the center line of bore and the center line of acceleration of the gun.
9. A mount for machine guns embodying a support, a yoke rotatably mounted thereon, a cradle trunnioned in the yoke and 70 adapted to secure a gun, the axis of the trunnions passing through the center of gravity of the recoiling parts of the gun when in battery.
10. A mount for machine guns embodying a support having a trail, a yoke rotatably mounted thereon, a cradle trunnioned in the yoke and adapted to secure a gun, the trunnions being positioned to such an amount in rear of the center of gravity of the gun that, in battery, the center of gravity may be substantially in line with the trail of the support and at the end of recoil the center of 75 gravity will lie in a plane perpendicular to the center line of the gun and passing through the forward attachment of the gun to the cradle.
11. A mount for machine guns embodying a support having a trail, a yoke rotatably mounted thereon, a cradle trunnioned in the yoke and adapted to secure a gun, the trunnions being positioned to such an amount in rear of the center of gravity of the gun both 80

in battery and at the end of recoil that the center of gravity, in the former position, will be substantially in line with the trail of the support.

12. A mount for machine guns embodying a support having a trail, a yoke rotatably mounted thereon, a cradle trunnioned in the yoke and adapted to secure a gun, the trunnions being positioned in rear of the center of gravity of the gun both in battery and at the end of recoil.

13. A mount for machine guns embodying a support having a trail, a yoke rotatably mounted thereon, and a cradle trunnioned in the yoke and adapted to secure a gun, the

15 trunnions being positioned in rear of the normal center of gravity of the gun so that said center of gravity will be substantially in prolongation of the trail.

14. A mount for machine guns embodying a support having a trail, a yoke rotatably mounted thereon, a cradle trunnioned in the yoke and adapted to secure a gun, said trun-

19 nions being located midway between the center line of bore and the center line of acceleration of the gun and but a short distance above the base of the yoke so that in the position of normal elevation the gun will lie close to the trail.

20 15. A cradle for machine guns embodying plates, formed with apertures for the reception of gun attaching bolts, and spacers connecting the plates and positioned to sup-

port the gun in the exact position of its attachment.

16. A cradle for machine guns embodying means whereby a gun may be attached thereto, and means for supporting the gun in the exact position of its attachment.

17. A mount for machine guns embodying a socket member, a yoke having a hollow pindle mounted thereby, and a gun cradle trunnioned in the yoke and extending on either side of the socket member but not ob-

structing the hollow pindle whereby the latter may vertically receive an antiaircraft adaptor.

18. A tripod including a standard, a cradle trunnioned in said standard, the axis of the trunnion of said cradle having a point in common with the axis of rotation of the standard and means for securing a gun in the cradle whereby the center of gravity of the gun will be forward of the trunnion axis and the trunnion axis will lie above the axis of the bore of the gun.

19. A tripod including a standard, a cradle trunnioned in the standard and means for securing a gun in said cradle whereby the center of gravity of the gun will be forward of the trunnion axis and the trunnion axis will lie above the axis of the bore of the gun.
